UNITED STATES PATENT OFFICE.

GEORGE W. CAMPBELL, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING-MACHINE.

1,332,971.

Specification of Letters Patent. Patented Mar. 9, 1920.

Application filed March 30, 1918. Serial No. 225,633.

To all whom it may concern:

Be it known that I, GEORGE W. CAMPBELL, a citizen of the United States, residing in Hartford, in the county of Hartford and 5 State of Connecticut, have invented certain new and useful Improvements in Typewriting-Machines, of which the following is a specification.

This invention relates to the construction 10 of paper-carriages of typewriting machines, and to means for supporting and guiding the carriages.

The improvements belong to the class of portable typewriting machines in which 15 compactness, lightness, reliability and low cost of manufacture are sought.

I construct the carriage frame principally 20 of sheet-metal, which is light, inexpensive and compact. The carriage comprises a sheet-metal struck-up body portion and ends which rise therefrom to support the platen, upon the front of which the types strike.

Said body portion preferably comprises 25 front and rear bars which, for strength and stiffness, are made angular in cross-section. The front bar may constitute the floor portion of the carriage, and it is made in angular cross-section in such a way as to form a longitudinal groove struck up in the bottom of the floor. A companion groove, 30 forming the front rail upon which the carriage runs, coöperates with the first-mentioned groove to form a raceway for a set of rolls upon which the floor of the carriage 35 is supported and guided. This supporting frame is preferably located near the forward portion of the carriage, so as to constitute the main support of the weight of the carriage; and there is also provided for 40 the carriage a rear roll to run upon a track which is also formed upon said frame.

Said supporting frame is preferably used 45 for shifting the carriage thereon up and down, to enable different types to print; and suitable hooks or guards are provided for preventing the carriage from rising accidentally from the rolls at either front or rear.

It is found, in practice, that the rail portion 50 of the supporting frame may be made of sheet-metal, and that the rails and grooves may be successfully struck up and used without grinding or otherwise exactly finishing either the tracks or the groove in the carriage, and that the carriage runs freely

without liability of sticking at any point, and is firmly supported against shaking in all ways.

Other features and advantages will hereinafter appear. 60

In the accompanying drawings,

Figure 1 is a sectional side elevation, taken about centrally, of a front-strike portable typewriting machine embodying the present improvements. 65

Fig. 2 is a plan of the carriage.

Fig. 3 is a plan of the rail frame upon which the carriage is supported and shifted up and down.

Fig. 4 is a perspective of the floor portion 70 of the carriage, detached.

The paper-carriage comprises front and rear body portions 10, 11 in the form of angle-bars and end plates or portions 12, 13 rising therefrom; all of these parts being 75 made of sheet-metal and secured together by means of rivets 14 passing through suitable ears 15 formed in the end plates. The body portions 10, 11, may also be secured together by stiffening members 15 if desired. Journaled in the latter is an axle 16 carrying a platen 17, around which the work-sheet is fed to position to be struck by the types 18 carried upon the forward ends of type-bars 19, the latter being suitably fulcrumed at 80 20 and operated by links 21 and bell-crank 22, the latter connected to key-levers 23.

The front or body portion 10 of the carriage is formed with a struck-up or inverted 85 V-groove 24, which not only stiffens the bar 90 and thus conduces to rigidity, compactness and low cost, but also coöperates with a V-rail or track 25 to form a raceway 26 in which run rolls 27 to support and guide the carriage, said rolls being set at right angles 95 to one another and connected by a suitable spacer 28 to form a truck.

The carriage is held down upon the rail 25 by means of a guide-roll 29, which runs upon the under side of the rail 25 to prevent lifting of the carriage therefrom, said roll 29 being pivoted upon the lower end of an arm 30 which projects downwardly and forwardly from the central portion of the carriage-floor, to which it is secured. 100 105

The struck-up groove 24 in the carriage-body is formed at about the middle portion of the bar 10, considered from front to rear, so that portions of the bar extend both forwardly and rearwardly from the grooved 110

portion, thus making a bar having a double angular (or corrugated) cross-section, which is very compact and rigid.

At about the middle of the rear angle-bar 11 of the carriage is attached a pendant bracket 31, carrying a roll 32 to run upon a rear rail 33. The front and rear rails form portions of a frame, which, in this case, shifts up and down to enable different types to print. The roll 29 previously described prevents the forward portion of the carriage from overthrowing upwardly at the shifting operation, and a hook 34 formed upon the lower end of the bracket 31 of the rear roll extends under and close to the rear rail 33, to prevent accidental lifting of the carriage at the rear side thereof. The rear rail 33 is preferably in the form of a struck-up flange provided upon the upper edge of a vertical plate 35 which forms the body of the shift-frame; side plates 36 extending forwardly, one at each end of the vertical plate 35, and having pivotal connections at 37, 38 to upper and lower guiding arms 39, 40, the latter journaled upon the main frame 41 of the typewriting machine.

The track 25 is secured to the side plates 36, and preferably by suitable angle-plates 36^a; the plate 35 being secured to said plates 36 by ears 35^a on said plate 35.

Said rear plate of the shifting frame is preferably stiffened by forming it with a U-shape flange 42, to cause it to resemble a hook in cross-section, as shown at Fig. 1, the upper portion of the hook forming the rear rail 33 upon which the carriage runs, and the bracket 31 which carries the rear roll 32 has the finger 34 hooking under said rail, to prevent lifting of the rear portion of the carriage.

The carriage movements may be controlled by escapement mechanism comprising a rack 44 on the carriage, which meshes with a pinion 45, the latter connected to an escapement wheel 46 of ordinary construction and operation. Said rack may be carried upon arms 47 pivoted to the side plates of the carriage to swing the rack up away from the pinion, to release the carriage from the control of the escapement mechanism.

Variations may be resorted to within the scope of the invention, and portions of the improvements may be used without others.

Having thus described my invention, I claim:

1. In a typewriting machine, the combination of a carriage comprising a sheet-metal floor portion or base and ends rising therefrom, said floor portion having a struck-up groove, a track underlying said floor and formed with a groove to coöperate with the first groove to form a raceway, rolls in said raceway, an arm extend-

ing down from said floor beneath said track, and a roll upon said arm to hook under said track to hold the carriage down upon the rolls.

2. In a typewriting machine, the combination of a carriage comprising a sheet-metal floor portion or base and ends rising therefrom, said floor portion having a struck-up groove, a track underlying said floor and formed with a groove to coöperate with the first groove to form a raceway, rolls in said raceway, an arm extending down from said floor beneath said track, a roll upon said arm to hook under said track to hold the carriage down upon the rolls, and means, including a second track to coöperate with said rolls to support and guide the carriage.

3. In a typewriting machine, the combination of a frame having a V-groove therein forming a track, a carriage having a floor provided with a complemental inverted V-groove to surmount said track, roller bearings running in said grooves, and an arm pendent from said carriage and having a roller to catch under the projecting portion of said track at the apex of the V to prevent the carriage from lifting and thereby enabling the rollers to serve as guides and prevent forward and backward shake of the carriage.

4. In a typewriting machine, the combination of a frame having a V-groove therein forming a track, a carriage having a floor provided with a complemental inverted V-groove to surmount said track, roller bearings running in said grooves, an arm pendent from said carriage and having a roller to catch under the projecting portion of said track at the apex of the V to prevent the carriage from lifting, a rear track, a roller upon said carriage to run upon said rear track, and additional means to prevent the carriage from lifting from said rear track.

5. A typewriter carriage having a struck-up sheet-metal base or floor formed with a longitudinal, inverted V-groove to coöperate with a V-groove in a track frame to form a raceway for rollers, and ends rising from said base to support a platen, said carriage having a roller hook to catch under the projecting portion of the track frame beneath the rollers so as to run on the apex of said V, to prevent the carriage from lifting from the track frame.

6. In a typewriter, the combination with a platen carriage and supporting means therefor, of front and rear roller bearings between said carriage and said supporting means, one of said bearings comprising a bracket having a roller mounted thereon and terminating in a retaining hook, said supporting means having a stiffening bead along one edge terminating in an inturned

flange, one surface of which comprises a track for said roller and the flange itself serving as a keeper for said retaining hook.

7. In a typewriter, in combination, a platen carriage, front and rear supports therefor, and front and rear roller bearings between said carriage and said supports, said rear bearings comprising a bracket having a roller mounted therein and terminating in a retaining hook, and said rear

support having a stiffening bead along one edge terminating in an inturned flange, the upper surface of which comprises a track for said rear roller and the flange itself serving as a keeper for said retaining hook. 15
